UNITED STATES PATENT OFFICE.

GEORGE H. LEWIS, OF ELYRIA, OHIO.

SHOE-HEEL SECTION OR LIFT.

1,242,213.

Specification of Letters Patent.

Patented Oct. 9, 1917.

Original application filed May 15, 1916, Serial No. 97,575. Divided and this application filed February 10, 1917. Serial No. 147,901.

To all whom it may concern:

Be it known that I, GEORGE H. LEWIS, a citizen of the United States, residing at Elyria, in the county of Lorain and State 5 of Ohio, have invented certain new and useful Improvements in Shoe-Heel Sections or Lifts; and I do hereby declare the following to be a full, clear, and exact description of the invention, such as will enable others 10 skilled in the art to which it appertains to make and use the same.

This application is a division of my application #97,575, filed May 15, 1916.

The invention of this application relates 15 to sections, or what are more commonly known as lifts, for shoe heels. One of the objects of the present invention is to provide a resilient lift for shoe heels which will adhere throughout its use closely to the 20 shoe heel itself with the use of little or no cement or other adhesive material.

Other shoe heel lifts which have hitherto been in use, so far as I am aware, have been made flat or concavo-convex in one form or 25 another. The flat heels are open to the objection that in use a seam soon opens up between the resilient lift and the portion of the shoe to which it is attached, which, in addition to forming an ugly opening, admits 30 dirt and water between the resilient lift and the other portion of the shoe, which, as can be readily understood, will be objectionable for a good many reasons.

I am aware that efforts have been made 35 to overcome this objection by fastening the flat lift to the leather or wooden section of the heel by the use of cement. This, however, causes considerable delay in applying the rubber heel to the shoe, in addition to 40 increasing the work of the shoe maker, and in fact, makes it impractical for people to apply the lifts to their own shoes. Moreover, in many cases the cement in time is dissolved or worn away and the seam 45 opens up.

I aim to produce a lift which can be applied very quickly to the shoe by the shoemaker, or which can be conveniently applied by any one to shoes, and which will always 50 adhere or be caused to cling closely throughout its whole surface to the heel of the shoe, and especially to the edges.

Another object of my invention is the provision of a heel lift which can be more conveniently and cheaply made than the con-

cavo-convex heel lifts now in use and which will, as nearly as practical, perform the same functions as said concavo-convex heel lifts. By tightly fastening, through the use of screws or nails, those portions of the edges 60 of the lift not automatically maintained in close contact with the surface to which the lift is attached, I overcome certain objections to those types of rubber heel lifts not so curved as to close all parts of the margins 65 of the inter-engaging surface of the lifts and heels, at the same time producing a lift which can be conveniently and cheaply made.

Other objects of my invention and the invention itself will be probably better understood from a description of an embodiment 70 of the invention.

Figure 1 is a side elevation of an embodiment of my invention.

Fig. 2 is a side elevation of a second embodiment of my invention, of greater curvature than the embodiment shown in Fig. 1.

Fig. 3 is a plan view of either embodiment shown in Fig. 1 or Fig. 2.

Fig. 4 is a section on the line 4—4 of 80 Fig. 2.

Fig. 5 illustrates an embodiment attached to a shoe heel.

Fig. 6 is a section taken along the line 85 6—6 of Fig. 3.

Referring now to the drawings and to the embodiments of my invention illustrated therein at 1 is shown a resilient heel lift made of rubber or some other suitable material possessing the necessary resiliency for 90 the purposes to be described. The upper surface of the lift is curved from one edge to another, in the embodiments illustrated, from the rear edge or corner 7 to the front end edge 8 or breast corners 9 and 10. This 95 upper surface 11 is preferably flat or substantially flat throughout, in order to make a close fit with the bottom of the shoe heel. The transverse elements of the upper surface, as will be shown, are straight, the lift 100 being curved in one direction only. The lower or bottom surface 12 of the lift is substantially parallel to the upper surface, so that the lift is substantially of uniform thickness throughout.

The lift is illustrated in normal position in Figs. 1, 2, 3, 4 and 6. However, when applied to the shoe heel, as illustrated in Fig. 5, the lift is flattened out, the upper flat surface engaging with the bottom flat sur- 110

face of the shoe heel to which it is attached by some suitable means, such as nails 15 passing through washers 16, which may be embedded in the lift. In trying to regain 5 its natural form, a major portion of the edges of the lift is forced against the corresponding portions of the shoe heel, tightly sealing the seam between the two thereat. Such portions as are not thus sealed are 10 sealed by the attaching nails, or other suitable means. Where flat surfaces are used, as illustrated in my invention, there will be no cavity between the surfaces for the accumulation of moisture and dirt, so that did any 15 leak in, it would be quickly expelled when pressure was applied to the lift below and the heel above. For practically all purposes, however, the lift may be quickly attached to the shoe without the use of other attaching 20 or sealing means than the nails, if the nails are properly placed to close the portions of the seam not automatically closed. Nails are driven into the shoe through the openings 20 and 21, at or closely adjacent 25 the center of curvature of the heel, to effectively close the seam thereat and thus seal that portion not sealed by the resiliency of the heel lift.

I have illustrated these embodiments of 30 my invention for the purpose of explaining the invention, and not that I wish to be limited to these embodiments or the details, as departures may be made therefrom without departing from the scope of the invention, such as set forth in the appended 35 claims.

I claim:

1. As an article of manufacture, a resilient shoe heel lift portion having the 40 general outline of a shoe heel and an upper surface normally curved in one direction only, the elements perpendicular to the direction in which the lift is curved being straight, said lift adapted to be flattened 45 against the under surface of the shoe heel when in use.

2. As an article of manufacture, a resilient shoe heel lift having the general outline of a shoe heel and a substantially 50 smooth upper surface normally curved from edge to edge in one direction only, the elements perpendicular to the direction in which the lift is curved being straight, said lift adapted to be flattened against the under 55 surface of the shoe heel when in use.

3. As an article of manufacture, a resilient shoe heel lift having the general out-

line of a shoe heel and upper and lower substantially smooth parallel surfaces normally curved from edge to edge in one direction 60 only, the elements perpendicular to the direction in which the lift is curved being straight, said lift adapted to be flattened against a heel surface when in use.

4. As an article of manufacture, a resilient shoe heel lift having the general outline of a shoe heel, with breast and end corners and upper and lower substantially smooth surfaces normally curved from 65 end to breast corners only, the transverse 70 elements of the lift being straight, said lift being flattened out against a shoe heel when in use.

5. In combination, a shoe heel, a resilient heel lift having the general outline of said shoe heel and having upper and lower substantially smooth parallel surfaces normally curved from edge to edge in one direction 75 only, the elements perpendicular to the direction in which the lift is curved being straight, and means to hold said lift flattened against and with its upper surface 80 engaging said shoe heel throughout.

6. In combination, a shoe heel provided with a substantially flat lower surface, a 85 shoe heel lift of resilient material having the general outline of a shoe heel and provided with an upper surface normally curved from end to end in one direction only, the elements perpendicular to the direction in 90 which the lift is curved being substantially straight, and means applied at or about the center of such normal curvature to attach said lift flat against the bottom of the shoe heel.

7. In combination, a shoe heel provided with a substantially flat lower surface, a shoe heel lift of resilient material having the general outline of a shoe heel and with a smooth upper surface normally curved 100 in one direction only, the elements perpendicular to the direction in which the lift is curved being substantially straight, and a lower surface substantially parallel to the upper surface, said lift being, when in use, 105 flattened against the under surface of the shoe heel and having its upper surface engaging the lower surface of the shoe heel throughout and means applied to the lift adjacent the center of such curvature to 110 close the seam thereat.

In witness whereof, I have hereunto signed my name this 7th day of February, 1917.

GEORGE H. LEWIS.
